UNITED STATES PATENT OFFICE

2,648,537

DISPLAY SIGN

Joseph Teitelbaum, Brooklyn, N. Y.

Application October 31, 1949, Serial No. 124,527

11 Claims. (Cl. 271—2.3)

1

This invention relates to advertising devices and more particularly to a display sign adapted to display continuous or progressive advertising matter.

An object of this invention is to provide an advertising device which is especially attractive and well adapted to hold an observer's interest.

A further object of the invention is to provide an automatic continuous or progressive display device using novel means for activating a strip of film placed therein.

Another object of the invention resides in the provision of concentric guide means for housing a film strip of larger size and design so that the film may be conveniently and easily fed before a transparent screen so as to novelly display an advertiser's wares.

A yet further object of the invention is to isolate the drive means of the invention from the film whereby the film is protected to a greater degree from deterioration due to grease or other oils.

Still further objects of the invention reside in the provision of a display sign that is strong, durable, highly efficient in operation, simple in construction and manufacture, easy to operate, relatively inexpensive, and extremely pleasing in appearance.

These, together with the various ancillary objects of the invention which will become apparent as the following description proceeds, are attained by this display sign, a preferred embodiment of which has been illustrated, by way of example only, in the accompanying drawings, wherein:

Figure 1 is a front elevational view of the display sign comprising the present invention;

Figure 2 is a vertical sectional view as taken along line 2—2 in Figure 1 and showing the guide means comprising a principal element of the invention in greatest detail;

Figure 3 is a horizontal sectional view as taken along line 3—3 in Figure 1 and showing the guide means comprising another element of the invention in its operative position;

Figure 4 is a vertical sectional view as taken along line 4—4 in Figure 2;

Figure 5 is another vertical sectional view this time taken along line 5—5 in Figure 1;

Figure 6 is a sectional detail showing how the film is entrained about the film engaging means of the display sign; and,

Figure 7 is an elevational detail showing how the roller bearings are journaled in the guide means of the present invention.

2

With continuing reference to the accompanying drawings wherein like reference numerals designate similar parts throughout the various views, reference numeral 10 generally designates the display sign comprising the present invention. This display sign 10 comprises a casing generally indicated by reference numeral 12 which includes several elements which may be bolted, screwed together, welded, or otherwise secured in any convenient and desirable fashion. These elements include a back plate 14, a top plate 16, a base plate 18 to which is secured in any convenient manner, such as by screws 20, a container 22 for the operative driving means of the invention. The container 22 also consists of a back plate 24, a bottom 26 and a front plate 28. Additionally, side plates 30 and 32 are provided for the container 22. Angle irons 34 are used to reinforce the structure in a convenient manner.

5 A pair of arcuate side pieces 36 and 38 which are secured to the top plate 16, bottom plate 18, and back plate 14 are provided. As shown best in Figure 7, one end of the plates 36 and 38 are provided with roller bearings 40 which are journaled within recesses 42 formed in the ends of the plates. The other ends of the plates 36 and 38 are secured to a frame member 44 which is also conveniently and removably attached to the top member 16 and the bottom or base member 18. A transparent plate of glass or plastic material and designated by reference numeral 46 is fitted into the frame 44 which may be formed of any suitable decorative molding. Secured to the bottom strip of the frame molding 44 is a tray 48 in which a fluorescent tube 50 is operatively secured so as to provide means for illuminating the interior of the casing 12.

40 Journaled within the top and bottom of the casing 12 are a pair of spaced shafts such as the one indicated by reference numeral 52. Each of the shafts have their lower end 54 extending without the bottom of the casing and into the chamber 22. The sprocket wheel 56 is secured to the end of the shaft 52 and a chain 58 is trained thereabout to transfer from sprocket wheel 60 driven by prime mover 62 which may be an electric motor or other similar device. A suitable reduction gear is used to reduce the speed of the motor 62 to the degree necessary for desirable actuation of the shafts 52.

An additional pair of spaced sprockets 64 and 66 are secured to the shaft 52 by any suitable means adjacent the top and bottom thereof. Co-axial with the shafts 52 are a plurality of spaced 55 arcuate guides such as those indicated by refer-

ence numerals 68, 70, 74, 76, and 78. On each of the vertically extending ends of these guides are secured roller bearings similar to the roller bearing 40 secured to the plate 38 which is best shown in Figure 7 in order to reduce friction on the film.

The film or elongated strip of paper or cloth having advertising matter there printed upon designated by reference numeral 80 for convenience is formed of a material strong enough to resist tearing due to any friction caused during passage about the arcuate guides and is entrained about the sprocket wheels 64 and 66 on the shafts 52 and in turn as can be seen through reference to Figure 2 is entrained about guide 78 then about guide 76, then guide 74, then guide 72, then around guide 70 and about guide 68 to pass between guide 68 and plate 38 and thence to the other side of the sign. The strip 80 is preferably endless in construction and is strong enough to be continuously rotated to provide a clearly viewed advertising medium.

It is contemplated to trim the sign with colored neon lights as desired. Additional decorative moldings about the frame or casing may be easily applied. Additionally, the back wall 14 will be provided with a small trap door at the bottom for easy access and adjustment of the device.

Since this device is easily adapted to be used about corners, upright, or in any convenient manner, it may be easily used on subway trains, buses, and practically any other convenient place.

Since from the foregoing, the construction and advantages of this display sign are readily apparent, further description is believed to be unnecessary.

However, since numerous modifications and changes will readily occur to those skilled in the art after a consideration of the foregoing specification and accompanying drawings, it is not intended to limit the invention to the precise embodiment shown and described, but all suitable modifications and equivalents may be resorted to which fall within the scope of the appended claims.

Having described the invention, what is claimed as new is.

1. A reeling system installed in a casing comprising film engaging means journaled in said casing, a plurality of radially spaced substantially concentric guide means substantially concentric with said film engaging means secured to said casing, and drive means operatively connected to said film engaging means, said film engaging means comprising a shaft journaled in said casing, one end of said shaft extending without said casing, spaced sprockets secured to said shaft within said casing and adapted to receive a film trained therearound, and a sprocket wheel secured to said end of said shaft, and said drive means engaging said sprocket wheel.

2. A reeling system installed in a casing comprising film engaging means journaled in said casing, a plurality of radially spaced substantially concentric guide means substantially concentric with said film engaging means secured to said casing, and drive means operatively connected to said film engaging means, said film engaging means comprising a shaft journaled in said casing, one end of said shaft extending

without said casing, spaced sprockets secured to said shaft within said casing and adapted to receive a film trained therearound, and a sprocket wheel secured to said end of said shaft, and a chain trained about said sprocket wheel and operatively connected to a prime mover.

3. The structure of claim 2 wherein said guide means comprise a series of substantially concentric arcuate plates substantially co-axial with said film engaging means.

4. The structure of claim 3 including roller bearings secured to the vertical ends of said plates.

5. A reeling system installed in a casing comprising a pair of spaced shafts journaled in said casing, a plurality of substantially concentric plates secured to said casing substantially co-axial with said shafts, said plates being radially spaced, and drive means operatively connected to said shafts.

6. The structure of claim 5 including spaced sprockets secured to each of said shafts within said casing and adapted to receive a film trained therearound.

7. The structure of claim 6 wherein said shafts each have an end extending without said casing, sprocket wheels secured to said ends of said shafts, said drive means engaging said sprocket wheels.

8. The structure of claim 7 wherein said drive means comprise a chain trained about said sprocket wheel and operatively connected to a prime mover.

9. The structure of claim 8 wherein said guide means comprise a series of substantially concentric arcuate plates substantially co-axial with said film engaging means.

10. The structure of claim 9 including roller bearings secured to the vertical ends of said plates.

11. In a display sign having a display casing, a drive means container and a continuous display web in said casing, a web winding device comprising a pair of shafts mounted in spaced apart relation in the casing, a pair of web engaging sprockets on each of said shafts, a plurality of radially spaced loop-forming arcuate guides concentric with each of said shafts, said web being entrained over said shafts and said guides.

JOSEPH TEITELBAUM.
